MASS SPECTROMETRY

Harold W. Washburn and Clifford E. Berry, Pasadena, Calif., assignors to Consolidated Engineering Corporation, Pasadena, Calif., a corporation of California

Application April 30, 1945, Serial No. 591,010

5 Claims. (Cl. 250—41.9)

1

This invention is concerned with mass spectrometers. It provides improvements in apparatus for protecting an ion beam to be analyzed from the effects of static charges built up within the spectrometer to the end that the calibration of the apparatus remains unchanged over longer periods, so that the accuracy of analysis is improved.

A mass spectrometer is essentially an apparatus for producing ions and sorting them according to the ratio of their mass to their charge, i. e. according to their specific mass. A sample to be analyzed, for example a gas mixture, is ionized (for example, by electron bombardment) and the resulting ions are propelled by an electrical potential into an analyzer. The ions thus enter the analyzer as an unsorted beam, and in the analyzer are sorted under the influence of an electromagnetic field in accordance with their specific mass into a series of divergent homogeneous ion beams. The sorted ions are collected and discharged, the quantity of each kind of ions being measured by the amount of current that they discharge upon collection.

In one type of mass spectrometer, ionization of the molecules is accomplished in an ionization chamber, for example by bombardment with an electron beam. The resulting ions are forced through a plurality of collimating electrodes having oriented slits or apertures therein, and emerge into the analyzer tube as an unsorted beam.

It has been found that some types of ions formed in a mass spectrometer tend to lodge upon dielectric surfaces within the apparatus and to build up static charges on these surfaces. The gradual accumulation of such charges as a result of this and other phenomena affects the calibration of the apparatus. The effect is particularly marked at an insulator which is employed as a spacer between the collimating or propelling electrodes, and we have discovered that these may serve a double function if they are constructed in the form of a shield or baffle which obstructs the space between the ion beam and the insulator. In this manner the effect of the static charge upon the ion beam is minimized. The baffle, however, may be an integral element. Accordingly, our invention contemplates the combination in a mass spectrometer which comprises an insulator disposed within the apparatus in such position that ions may lodge upon it to create a static charge, means for producing an ion beam, a conductive baffle disposed between the insulator and the path of the beam and

2

spaced from both and conductive means for discharging current from the baffle. In one form of the invention, electrodes are spaced from each other within the spectrometer along the ion beam path by an insulator, and the ion beam is protected from the charge at the insulator by baffles spaced from each other between the electrodes and attached respectively to them. A preferred form of the invention contemplates in a mass spectrometer the combination which comprises collimating electrodes, each having an aperture therein through which an ion beam is propelled, an insulating spacer between the collimating electrodes, a shield comprising overlapping baffles spaced from each other and disposed between the collimating electrodes and between the insulator and the beam, one of the baffles being connected to (and preferably formed integrally with) one collimating electrode and the other baffle being connected to (and preferably formed integrally with) the other collimating electrode. The shield thus obstructs the straight line paths between the insulator and the ion beam and effectively shields the latter from the effect of static charges built up on the insulator. As indicated above, the baffles should be of conductive material and preferably are formed integrally with the electrodes. The baffles overlap in a direction substantially parallel with the beam and transverse to substantially any straight line which could be drawn between insulator and ion beam.

These and other features of the invention will be understood more thoroughly in the light of the following detailed description, taken in conjunction with the accompanying drawings in which:

Figs. 1 and 2 are longitudinal sections taken at right angles to each other through the head of a mass spectrometer adapted to the practice of our invention; and

Fig. 3 is a schematic diagram of a mass spectrometer equipped with the head of Figs. 1 and 2.

Referring to the drawings, it will be seen that the apparatus comprises a cylindrical head 10 the rear of which connects with a gas inlet tube 11 of insulating materials. Within the head there is an inlet electrode 12 in the form of a metallic tube which communicates with the gas inlet conduit at its rear and which is partially closed at its front end by a cylindrical electrode plate 13 having a transverse slot to accommodate an electron beam 14.

The electron beam is produced by an electron gun 16 mounted outside a metallic block 17 which

encloses an ionization chamber 18 within which the slotted electrode plate is disposed. (See Figs. 1 and 2).

The electron beam enters the ionization chamber through an aperture 19 which is in line with the slot in the inlet electrode, passes through the slot, and thence through an aperture 20 in the opposite side of the block to an electron catcher 21.

The front of the ionization chamber is formed by a propelling electrode 22 separated from the block by an insulator 23 and provided with a slit S₁ that is substantially in line with the slot in the inlet electrode. A second propelling electrode 24 provided with a slit S₂ is disposed in front of the first propelling electrode with the slit S₂ in line with the slot in the inlet electrode and the slit S₁. The two propelling electrodes are spaced from each other by a ring 25 of quartz or similar insulating material enclosing a chamber 26.

The insulating ring 25 separating the two slit electrodes 22, 24 tends to accumulate static charges from vagrant ions which adhere to its inner surface. These static charges are prevented from exerting an influence on the ion beam passing from the slit S₁ through the slit S₂ by means of a shield comprising an inner baffle 27 and an outer baffle 28. These two baffles are spaced from each other but overlap slightly so that they obstruct straight-line paths from the insulator ring to the space through which the ion beam passes.

It is desirable to introduce a transverse component in the potential employed to propel the ions from the ionization chamber through the slits S₁, S₂ into the analyzer tube. In the type of apparatus illustrated this is accomplished by making the first propelling electrode in the form of two sections 22A, 22B. These sections define the slit S₁ but are spaced from each other and are adapted to be energized separately as described hereinafter. In consequence the outer baffle 28 is likewise slit into two opposed segments 28A, 28B separated by a gap adjacent the slit S₁, and these segments are integrally formed respectively with the segments 22A, 22B of the first propelling electrode.

The inner baffle is a continuous ring formed integrally with the second propelling electrode.

The baffled chamber communicates with an analyzing chamber 29 of the mass spectrometer through the slit S₂ in the second propelling electrode, which latter is fastened to an analyzer tube 30 that forms the wall of the analyzing chamber.

Referring now to Fig. 3, it will be observed that the head 10 of the mass spectrometer and the attached analyzer tube 30 are enclosed within an envelope 31, through the wall of which the gas inlet tube 11 projects. A high degree of vacuum is maintained within the envelope by means of vacuum pumps (not shown) connected to the tube.

The molecules of a gas sample admitted into the ionization chamber through the inlet electrode are bombarded by the electron beam passing through the slot at its end and thus converted into ions. These ions are propelled as an unsorted beam into the analyzer tube by electrical potentials established between the several electrodes in the head by an electrical system shown schematically at the left of Fig. 3.

A battery or other direct current supply 40 is connected to the ends of a potentiometer 41,

The positive end of this potentiometer and its slider are connected through a switch 42 to a condenser 43. A potential dividing network is connected across this condenser and takes the form of a resistor or potentiometer 44 in series with a parallel pair of resistors or potentiometers 45, 46 which are in turn connected to ground at the negative end of the network.

The inlet electrode is connected to the positive side of the network at the slider of the potentiometer 44. One segment of the first propelling electrode is connected to the slider of the potentiometer 45; the other segment of this electrode is connected to the slider of the potentiometer 46, and the second propelling electrode is connected to the negative end of the network and to ground.

In the operation of the apparatus a sample of gas to be analyzed is admitted through the gas inlet tube and passes through the slot in the inlet electrode, where it is bombarded by the electron beam. For optimum results (as described and claimed in co-pending application Serial No. 590,917, filed April 28, 1945 now Patent No. 2,475,653 issued July 12, 1949) the current producing this electron beam should be maintained constant, which result can be obtained by observing the current at the electron catcher by a conventional meter (not shown) and adjusting the electron current (for example, by the means shown in co-pending application Serial No. 590,917, filed April 28, 1945).

Molecules of the gas sample are thus ionized and the resulting ions are propelled as an unsorted ion beam from the inlet electrode through the slots S₁, S₂ into the analyzer tube. There the unsorted beam is separated into a plurality of diverging homogeneous ion beams B₁, B₂, B₃ by means of an electromagnetic field produced in the analyzer tube by an electromagnet (not shown). Any one of the diverging beams may be focussed on the exit slit at the end of the analyzer tube, so that it passes therethrough and strikes an ion collector. The current thus established in the ion collector is amplified and recorded by suitable apparatus and serves as an index of the quantity of that particular type of ions produced from the sample.

The position of the ion beams with respect to the exit slit may be changed by varying the electromagnetic field in the analyzer tube or by varying the propelling potentials. The latter method is preferred and may be practiced as follows:

The switch 42 in the energizing network is closed and the condenser 43 is charged to an appropriate level. Then the switch is opened and the condenser is permitted to discharge through the potential dividing network and the several electrodes in the head of the mass spectrometer. In this way the propelling potentials between the several electrodes gradually decay, while maintaining relative values.

It will be observed, however, that the potentials may be adjusted by suitably setting the potentiometers. Thus the potential at the inlet electrode may be adjusted by varying the setting of the potentiometer 44. Likewise, the potentials at the two segments 22A, 22B of the first propelling electrode can be varied by varying the setting of the potentiometers 45, 46. In this way the ion beam may be adjusted to give optimum results at the exit slit and ion collector.

If it is desired to operate without employing a transverse component of potential for focussing purposes at the slit S₁, the first propelling elec-

trode can be built as a single electrical unit, in which case the outer baffle 28 attached thereto may be a continuous annulus.

It should be observed that static charges may also tend to accumulate on the insulator ring 23 which separates the electrode segments 22A, 22B (that define the slit S₁) from the block 17. As described and claimed in co-pending application Serial No. 590,917, filed April 28, 1945, the tendency of these charges to de-focus the ion beam may be overcome by a conductive ring 50 disposed inside the insulator ring and substantially covering it, save for a gap which separates the conductive ring from the segments. The conductive ring is mechanically and electrically connected to the block so that it is under substantially the same potential.

We claim:

1. In a mass spectrometer, the combination which comprises electrodes spaced from each other along the path of an ion beam, an insulator holding the electrodes apart, and a shield disposed between the insulator and the ion path and comprising conductive baffles spaced from each other and attached respectively to the electrodes.

2. In a mass spectrometer, the combination which comprises collimating electrodes each having an aperture therein through which an ion beam is propelled from one electrode to the other, an insulating spacer disposed between the collimating electrodes, and a shield comprising overlapping conductive baffles spaced from each other and disposed between the electrodes and between the spacer and the path of the beam.

3. Apparatus according to claim 2 in which one baffle is fastened to one electrode and supported thereby in electrical contact therewith and the other baffle is similarly fastened to the other electrode.

4. Apparatus according to claim 2 in which one baffle is formed integrally with one electrode and the other baffle is formed integrally with the other electrode.

5. In a mass spectrometer, the combination which comprises a first collimating electrode comprising two segments insulated from each other and adapted to be separately energized, the two segments being separated from each other by an aperture, a second collimating electrode having an aperture matching that between the two segments, means for propelling the ion beam through the two apertures, an insulator disposed between the two electrodes and holding them apart, and a shield disposed between the two electrodes and between the insulator and the path of the ion beam and comprising a first conductive baffle fastened to and in electrical contact with the second collimating electrode, and a pair of conductive baffles spaced from each other and the first conductive baffle, but overlapping the latter and fastened respectively in conductive relationship with the segments of the first collimating electrode.
